UNITED STATES PATENT OFFICE.

WILLIAM P. WOOD, OF PAWTUCKET, RHODE ISLAND, ASSIGNOR TO JENCKES SPINNING COMPANY, OF PAWTUCKET, RHODE ISLAND, A CORPORATION OF RHODE ISLAND.

HEDDLE FOR LENO-WEAVING MACHINES.

1,132,644.

Specification of Letters Patent.

Patented Mar. 23, 1915.

Application filed November 8, 1911. Serial No. 659,079.

To all whom it may concern:

Be it known that I, WILLIAM P. WOOD, a citizen of the United States, residing at Pawtucket, in the county of Providence and 5 State of Rhode Island, have invented certain new and useful Improvements in Heddles for Leno-Weaving Machines; and I do hereby declare the following to be a full, clear, and exact description of the invention, such 10 as will enable others skilled in the art to which it appertains to make and use the same.

The invention relates to doup heddles such as are adapted for use in weaving 15 gauze or leno fabrics. Heddles of this type as heretofore constructed have usually been provided with doup loops formed of twine or similar flexible material which are rapidly worn, so that frequent repair or 20 renewal of the doups is required with a resulting increase in the cost of manufacture. Attempts have been made to substitute wire for the doup cords or threads, but such wire doups have not proved satisfactory, owing 25 principally to the increased wear upon the warp threads due to the construction of the wire doup, or to the fact that the warp threads, which were not connected with the doup harness, were liable to catch on the 30 ends of the wire doups during the forming of the sheds, and thus interfere with the proper operation of the harness.

It is the object of the present invention to provide a novel and improved construction 35 of doup heddle which will enable the doup loops to be formed of wire or any other desired material without danger of producing undue wear upon the warp threads, or of interfering with the proper forming of the 40 sheds.

To this end the invention consists in the features of construction and combination of parts hereinafter described and referred to in the claims.

The invention will be readily understood 45 from an inspection of the accompanying drawings, and the following detailed description of the heddle illustrated therein.

In the drawings Figures 1 and 2 are dia- 50 grammatic views illustrating the mode of operation of a heddle embodying the invention in weaving leno or gauze fabric; Fig. 3 is a side elevation of a heddle embodying the invention in its preferred form; Fig. 4 55 is an edge view of the heddle shown in Fig.

3; Fig. 5 is a view similar to Fig. 3 showing the doup loop in a different position; and Fig. 6 is an edge view of the heddle with the parts in the position shown in Fig. 5.

As shown in the drawings the heddle consists of a thin metal strip 1 and a doup loop 2 which is preferably formed of comparatively thin wire. The doup loop is bent at its upper end to form an eye 3 through which the doup warp T passes, and to form 60 two legs 4 which pass through holes or slits 5 formed in the heddle strip 1.

In general the mode of operation of the heddle in weaving leno fabric is the same as the usual form of heddle in which the 70 doup loop is formed of twine or cord. As shown in Figs. 1 and 2, the doup warp T passes through a heddle 6 and then through the eye 3 of the doup loop, from which it leads to the fabric. The warp thread T', 75 which is not operated by the doup, and which for convenience may be called the ground warp, passes through a heddle 7 and thence to the fabric. The heddles 1, 6 and 7 have their upper ends connected by cords 80 with a jacquard mechanism, and are provided at their lower ends with the usual lingoes 8. The heddle strips 1 pass through guides 9 which prevent turning or twisting of the heddle. The lower ends of the doup 85 wires are secured by cords 10 to a frame 11 which is moved up and down by connection with the jacquard mechanism.

In forming a leno shed the heddle 6 and frame 11 move down to carry the doup 90 thread below the ground thread, the legs of the wire doup 2 drawing down through the holes 5 from the position indicated in Figs. 3 and 4 to the position indicated in Figs. 5 and 6. The heddle 6 and frame 11 then 95 move up into the position indicated in Fig. 2, carrying the doup thread up on the opposite side of the ground thread and thus carrying the doup thread about the ground thread to twist the warp thread between successive picks. In weaving plain fabric the heddles for the doup warp and the heddle for the ground warp move alternately up and down in the usual manner. A number of warp threads may be led through the 105 doup loop and the heddles for the doup warps may be operated by the jacquard to secure different patterns, as is usual.

In order that the doup warp thread or threads may be free to draw through the 110

end of the doup loop without unduly wearing or straining the doup warp, means is provided for preventing the clamping of the doup warp between the end of the doup 5 loop and the heddle strips 1 when the doup is drawn down into the position indicated in Figs. 5 and 6. In the construction shown, clamping of the doup warp between the end of the doup and the heddle strips is prevented by so shaping the end of the doup loop with relation to the strip 12 between the holes 5 that the legs of the loop engage the edges of the strip 12 before the end of the doup brings up against the strip, and 10 thus prevent the engagement of the extreme end of the doup with the strip. As shown, the upper end of the doup loop is contracted so that it is narrower than the strip between the guiding holes 5 in the heddle strip. 15 With this construction, when the doup is drawn down into the position indicated in Figs. 5 and 6, the upper end of the doup passes through which the doup warp is held above and out of engagement with the strip 20 12 between the guiding holes 5, so that there is no danger of clamping the doup thread between the end of the doup and the heddle strip, and thus abrading or breaking the warp. 25 30 In order that the ground warp may pass freely over the eye 3 of the doup loop as the ground warp travels up and down the side of the doup heddle, the heddle is provided with means for guiding the ground warp 35 over the end of the doup, and thus preventing such engagement of the ground warp with the end of the doup as would interfere with the proper movement of the ground warp. In the construction shown, 40 provision is made for thus guiding the ground warp over the end of the doup by forming a recess 13 in the side of the heddle strip 1 within which the end of the doup wire is pocketed and protected from engagement with the ground warp while this 45 warp is passing over the end of the doup. The recess 13 preferably extends for some distance above the holes or slits 5, so that the end of the doup will be effectively protected from engagement with the ground warp passing over it even if the end of the doup projects somewhat through the heddle strip. In this construction the face of the strip 1 on opposite sides of the recess 13

forms guides for guiding the ground warp 55 over the end of the doup and preventing its passing between the end of the doup and the heddle strip.

While it is preferred to form the guides for directing the ground warp over the ends 60 of the doups and to prevent clamping of the doup warp by the doups in the manner shown and described, it will be understood that the specific form of heddle and doup shown and described is not essential to the 65 broader features of the invention, and may be varied and modified without departing therefrom.

Having explained the nature and object 70 of the invention, and specifically described one construction of heddle in which it may be embodied, what I claim is:—

1. A heddle for leno weaving comprising a doup loop, a heddle strip provided with holes through which the legs of the doup 75 pass and a strip between the holes, means for guiding the main warp over the end of the doup and means for preventing clamping of the doup warp by the doup, substantially as described. 80

2. A heddle for leno weaving comprising a heddle strip provided with holes through which the legs of the doup pass and with guides for guiding the ground warp over the end of the doup, and a doup having its 85 end shaped to prevent clamping of the doup warp between said end and the heddle strip between the holes, substantially as described.

3. A heddle for leno weaving comprising a heddle strip, two holes through the strip 90 for the passage of the doup loop, a wire doup having its legs passed through the holes in the strip and having its end contracted to prevent engagement of the eye at the end of the doup with the strip between 95 the holes, and a recess in the heddle strip for receiving the end of the doup, substantially as described.

4. A heddle for leno weaving comprising a heddle strip 1, provided with slits 5, and 100 a recess 13, and a wire doup 2 provided with legs 4 passing through the slit, and with a contracted eye 3, substantially as described.

WILLIAM P. WOOD.
